UNITED STATES PATENT OFFICE.

LOUIS NEWMAN, OF CHICAGO, ILLINOIS.

PASSENGER TRAIN AND PLATFORM.

Application filed December 15, 1917. Serial No. 207,372.

To all whom it may concern:

Be it known that I, LOUIS NEWMAN, a citizen of the United States, residing in Chicago, in the county of Cook and State of Illinois, have invented a new and useful Improvement in Passenger Trains and Platforms, of which the following is a specification.

This invention relates in general to passenger trains and platforms at which the trains may receive and discharge passengers, and has particular reference to intra-urban and suburban trains where it is desired to take care of both small and large crowds 10 economically and quickly. The invention will hereinafter be described in connection with an elevated railway system although it will be manifest as it is better understood that the invention has other and valuable application in subways, railway trains, surface lines and the like.

A principal object of the present invention is the provision of a train and attendant instrumentalities, which may discharge 25 and receive passengers in large numbers and in the shortest possible time.

A still further object of the invention is the provision of a train and associated instrumentalities, which will economize the 30 space on the platform so that crowds of persons can be loaded and unloaded, without crowding, from a platform of restricted size.

A still further object of the invention is the provision of a train and associate instrumentalities, which may operate upon the pay-as-you-enter system at such hours as the traffic conditions permit and which may be readily converted to permit the fares to be collected before the persons board the 40 train during the rush hours of the service.

A further object of the invention is the provision of a train which will require the services of fewer attendants than is usual on elevated railroads, subways and the like.

A still further object of the invention is the provision of a train adapted to operate under the pay-as-you-enter system and so constructed and arranged that the passengers may enter quickly at the stations and the 50 fares be expeditiously collected before the train arrives at its next stop.

A still further object of the invention is the provision of a train and platform constructed and arranged to separate the leaving passengers from those boarding the train and this without requiring said leaving pas-

sengers to cross the platform or in any way mingle with those desiring to board the train.

A still further object of the invention is 60 the provision of a train of cars which will require no gate keeper for the platform at the ordinary station in the residence district, and in the business district except at rush hours, and which will reduce the number of 65 guards required for the operation of a train to a minimum thereby effecting a material saving in the cost of operating the road.

Numerous other objects and advantages of the invention will be apparent as it is better 70 understood from the following description when considered in connection with the accompanying drawing illustrating a preferred embodiment thereof.

On the drawings, 75
Figure 1 is a plan section of a part of the train and platform embodying my present invention;

Fig. 2 is a side view partially in elevation and partially in perspective of the same; 80

Fig. 3 is a partial view similar to Fig. 1 showing a different arrangement of the train and platform.

Fig. 4 is an enlarged section through one of the cars shown in the other figures; 85

Fig. 5 is a partial view similar to Fig. 4 and of the same car with the parts differently arranged; and

Figs. 6 and 7 are enlarged sectional detail views of the partition used in the pay-as- 90 you-enter enclosure on the car.

For the purpose of illustrating my invention, I have shown the same embodied in a train consisting of a number of cars indicated on the drawing at 10, 11, 12, 13 and 14, 95 connected in any usual or preferred fashion and communicating with each other by vestibules 15, the communication being such that a person may pass easily and safely from one car to the other. The train of 100 cars thus mentioned is shown on the drawing at a platform 17 having one or more entrance stairways 18 at the top of which is a cage or space 19 for a fare taker. However, as already stated, the invention contemplates the operation of the train either to collect the fares on the train itself or at the entrance to the platform, and it will therefore be understood that the fares may or may not be collected by the fare taker in 110 the cage or cages 19 as conditions of traffic may render desirable.

In the present instance, to illustrate an embodiment of my invention, it will first be described as arranged upon the pay-as-you-enter (the car) system. Every other car, in 5 the present embodiment 11 and 13, is provided with a pay-as-you-enter entrance 21, which is located at the center of the car and each car is provided with an exit 22 at its end or ends connected with adjacent cars. 10 An enclosure is formed within the cars 11-13, which may be termed the entrance cars, by walls or partitions 23 having door spaces 24 communicating with the body portions or ends of the car. This enclosure 15 is preferably divided into a main part 25 adjacent the entrance 21 and a passageway 26 at the opposite side, the division being made by a partition as will now be described. To one wall part 23 a foldable 20 two-part partition section 27 is removably pivoted, this section being shown in enlarged view in Fig. 7. The parts 28 and 29 of the section are merely hinged together at 31. The part 28 which is adapted for attachment to the wall part 23 is provided 25 with a pair of downwardly extending hooks 32 adapted to engage eyes 33 in the wall part and the part 29 is provided with similar hooks 34 which may be engaged in eyes 30 35 bolted to a removable post 36 extending up at an appropriate location from the floor of the enclosure. An opening is provided between this post and a second post 37 to establish communication between the passageway 35 and main part of the enclosure, which opening is adapted to be closed by a foldable curtain or closure 38 carried by the post 36 and engageable with the post 37. A four-part partition section 39 connects the 40 post 37 with the opposite corresponding wall section 23. The parts 41, 42, 43 and 44 of this section are hinged together at 45 so that the section may be opened out as shown in Fig. 4 or collapsed or folded up as 45 shown in Fig. 5. One end part 44 is provided with hooks 46 like the hooks 32 and which engage in eyes 47 like the eyes 33 similarly arranged. When the partition section 39 is unfolded and placed in operative position it extends about a corner post 48 and from there extends to the post 37 to which it is engaged. The fare taker stands at 49 preferably upon a raised box or pedestal so that he can see easily throughout the car in 55 which he is stationed and also into and through the adjacent cars at each side, it being understood that the partition in the enclosure and its confining walls are low and therefore do not obstruct his view. Two doors 60 51 are provided to prevent passage between the enclosure and the body or ends of the car while the fares are being collected as will be later explained. It is intended that the enclosure shall be of a size to contain 65 comfortably from 25 to 40 or more persons

standing in the passageway 26 and in the main part 25. When the train pulls up at a station a door 52, normally closing the pay-as-you-enter entrance, is opened and the curtain 34 moved to permit ready communication between the passageway and main part of the enclosure. The entering passengers pass through the main part, fill the passageway and so much of the main part as is necessary or if there are only a few they are admitted merely to the main part. At this time the doors 51 are closed and the fare taker, after the train has left the station, collects the fares first from the persons in the passageway and opens one or both doors 51 to direct them into the body of the car and through the communication with adjacent cars into the adjacent cars also. He then collects the fares from the persons in the main part as they pass through the opening between the posts 36 and 37. If desired the curtain 38 may be drawn to cut off communication between the passageway and main part of the enclosure until the fares in the passageway are collected. 70 75 80 85 90

It will be noted that the partition may be arranged to permit the passengers to enter from the opposite side of the car, i. e., the top in Fig. 4, holes 53 being provided to receive the posts 36, 37 and 39, and eyes 54 being located on the partition parts 55 to receive the hooks 33 and 47. 95

In order that passengers may not enter through the exits 22, I provide platform separators indicated in Fig. 1 at 56, which prevent the leaving passengers from mingling with the entering ones. Stairways 57 communicate with the inside of the enclosure formed by the separators and the passengers are directed by the separators directly from the train exits to the stairways and away from the platform. The separators are spaced upon the platform at appropriate distances to permit the motorman located at 58 at the forward end of the train to easily stop with a pair of exits 22 located at an appropriate platform separator. It will be noted that the platform separators do not extend completely across the platform to permit ready passage of persons upon the platform from one end to the other so that they may easily station themselves at any desired pay-as-you-enter entrance, which preferably, for the convenience of passengers, is located for them by suitable signs (not shown). 105 110 115 120 125

Frequently express and local trains run upon the same track and stop at the same platform and the platform separators may be utilized, if desired, to separate the passengers desiring to board the local train from passengers desiring to board the express train. This may be accomplished by causing the two trains to stop at different locations. When the train is constructed 130

and arranged as indicated on the drawing, it will be noted that there are two platform separators between each pair of pay-as-you-enter entrances; or differently stated the 5 pay-as-you-enter entrances are presented only at alternate spaces between the platform separators. If the train were stopped one car back, that is the car 10 were stopped where the car 11 now stands, the pay-as-you-enter entrance would be disposed at other 10 spaces between the platform separators. These spaces may be labeled therefore alternately "Express" and "Local" stops, or if desired the same system may be used to direct 15 the passengers for trains leaving for different destinations.

The invention contemplates also the quick loading of the train without any obstruction from the separators or from the parts disposed 20 within the car to provide pay-as-you-enter facilities. In big cities the traffic is almost entirely in one direction at certain hours—to the business district in the morning and to the residence district in the evening. The passengers in the morning usually 25 board the train at a considerable number of successive stations and leave it at relatively few downtown stations and in the evening board the train at relatively few downtown stations and leave it at a considerable 30 number of stations in the residence district. Considering first the traffic down in the morning. The passengers board the train at the residence stations and usually in numbers 35 at the single stations sufficiently small to permit the fares to be collected on the pay-as-you-enter system and they may leave the train in large numbers through the platform separators unless the crowd be so great that all three doors at the sides of the car are necessary to facilitate the unloading, it being understood that center doors are provided in the car sides of all the cars whether arranged for the pay-as-you-enter 40 system or not. That is to say, cars 10, 12 and 14 also have side doors 50, which, except in rush hours, are kept closed. If it be desired to empty the train at a single station or to provide greater exit capacity than can 45 be provided by the exits 22, the platform separators are constructed to be moved out of the way as well be presently described and the partitions within the pay-as-you-enter enclosures can be collapsed by folding 50 up on their hinges and back against the sides of the enclosure walls and arranged as indicated in Figs. 3 and 5. Fig. 3 shows the arrangement of the collapsed platform separators as well.

55 Each platform separator consists of a main wall 61 to which are pivoted end walls 62 adapted to be swung, from the position shown in Fig. 2 where they co-operate with the sides of the car to form an enclosure, around into parallelism with the

main wall 61, preferably lying close against its outer face as indicated in Fig. 3. The wall 61 may form the railing of the stair or stair closure.

Returning home in the evening the fares 70 of the passengers can be collected as they enter the platform in the stations in the business section and all of the openings at the side of the train may be used as entrances—three to each car. The partition in 75 the pay-as-you-enter section is rendered readily positioned and removed so that after the business district is passed the train can operate on the pay-as-you-enter plan with little inconvenience to the fare taker. If 80 the platform separators are collapsed or moved out of the way during the rush hours they can readily be returned to the operative position shown in Fig. 2 and the entire system 85 operated upon the pay-as-you-enter plan.

Prior to my invention it has been generally the custom to station a guard between the cars at each pair of connected ends so that five, six and seven car trains require respectively four, five and six guards in addition to the motorman. A train constructed and operated in accordance with my present invention requires only half the number of guards for a train of even number of cars 90 and one guard or fare taker for the odd car if the train have an odd number.

Pneumatic or electric means are provided to permit the guards or fare takers stationed 100 in their respective enclosures to operate all the doors. The guard we will say in the enclosure of car 11 will operate doors 50 and 22 of car 10, doors 22 and 21 of car 11 and adjacent doors 22 of car 12, and in addition will of course operate the doors of 105 his enclosure. This control is simple and it is believed need not be shown on the drawing. Of course, if desired, each guard can open only the doors 21 and 22 of the car in which he is stationed, in which event the 110 passengers from adjacent cars pass through the vestibules and out of the exits in the cars provided with guards.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A passenger train, comprising a plurality of connected communicating cars, alternate cars having merely exits opening to the platform and the cars therebetween being provided with entrances from the platform for all said cars.

2. A passenger train, comprising a plurality of connected communicating cars, alternate cars having merely exits opening to the platform and the intermediate cars having entrances from the platform at their side centers for all the cars. 70
3. A passenger train, comprising a plurality of connected communicating cars, all of said cars having exits and alternate cars only having entrances from the platform. 75
4. A passenger train and a platform at which said train may stop to receive and discharge passengers, said train and said platform both having entrances and exits, a platform separator directing persons leaving the train directly to the platform exits thereby preventing them from mingling with persons boarding the train. 80
5. A passenger train and a platform at which said train may stop to receive and discharge passengers, said train and said platform both having entrances and exits, and platform separators forming with the side of the train an enclosure including a platform exit and a train exit to cause persons to pass directly from the train exit to the platform exit. 85
6. A passenger train and a platform at which said train may stop to receive and discharge passengers, said passenger train having exits and entrances and said platform having exits and entrances, and platform separators enclosing the exits of the platform and car and leaving an unobstructed passageway around said separators on said platform whereby to permit persons desiring to board the train access to the platform throughout its length. 90
7. A passenger train and a platform at which said train may stop to receive and discharge passengers, a plurality of exit stairways communicating with said platform, and platform separators enclosing each stairway and an exit portion of said train. 100
8. A passenger train and a platform at which said train may stop to receive and discharge passengers, stairways communicating with said platform adjacent the side of the platform at which the train may stop, and platform separators enclosing said stairways and forming with the exit portions of the car an enclosure for directing passengers from the train exits directly to said stairway. 115
9. The combination of a train composed of a plurality of cars having distributed exits and intermediate entrances, and means for preventing passengers from entering the train through said exits, said means including platform enclosures and stairways within said enclosures. 120
10. The combination of a passenger train, comprising a plurality of communicating cars provided with distributed exits and entrances intermediate said exits, doors for all said exits and entrances, and means for preventing passengers from entering the train through the exits when all said doors are open, said means comprising platform enclosures and stairways communicating with the platform inside said enclosures. 70
11. A passenger train, comprising a plurality of cars having distributed exits and separate entrances between said exits, a platform at which said train may stop, and having platform separators intermediate said entrances and enclosing said exits whereby to prevent persons leaving the train from mingling with those desiring to board the train and means forming exits from the separators outside the platform. 80
12. A passenger train and a platform at which said train may stop to receive and discharge passengers, said train having distributed exits and separate entrances, and platform separators forming enclosures about said exits and extending only partially across the platform and stairs communicating with said separators. 85
13. A passenger train and a platform at which said train may receive and discharge passengers, said platform having platform separators for preventing persons leaving the train mingling with persons desiring to board the train, said separators serving also to divide the platform into spaces between said separators and means forming exits from the separators outside the platform. 90
14. A passenger train and a platform at which said train may receive and discharge passengers, said train having a plurality of pay-as-you-enter entrances and exits remote from said entrances, and means for preventing persons desirous of boarding the train from entering through the exits, and for preventing persons leaving the exits from mingling with said persons desirous of boarding said train. 100
15. A passenger train and a platform at which said train may receive and discharge passengers, means on said train and platform for permitting said train to receive passengers either paying as they enter the train or as they enter the platform, said means comprising readily removable devices within the train for separating persons who have paid their fare from those who have not, and platform separators upon the platform for preventing persons entering the train through the train exits, said train separating devices being movable out of the way when the fares are collected as the persons enter the platform. 115
16. A passenger train and a platform at which said train may receive and discharge passengers, means on said train and platform for permitting said train to receive passengers either paying as they enter the train or as they enter the platform, said 120
- 130

means comprising platform separators for preventing passengers entering through the exits when the fares are collected in the train, said separators being movable to provide an unobstructed platform when the fares are collected as the persons enter the platform.

17. A passenger train and a platform at which said train may receive and discharge passengers, means on said train and platform for permitting said train to receive passengers either paying as they enter the train or as they enter the platform, said means comprising platform separators for preventing passengers entering through the exits when the fares are collected in the train, said separators being movable to permit entrance through the exits when the fares are collected as the persons enter the platform.

18. A passenger car having a central entrance and an enclosure within said entrance, said enclosure being divided into a passageway at the side of the car remote from said entrance and into a main part adjacent said entrance, and doors or gates for confining persons within said passageway until their fares are collected.

19. A passenger car having a side entrance and an enclosure within said entrance, said enclosure having a main part adjacent the entrance, and at the opposite side therefrom, a passageway connecting said main part with the ends of the cars and providing a fare taker station within said main part and adjacent said passageway.

20. A passenger car having a side entrance and an enclosure within said entrance, said enclosure having a main part adjacent the entrance, and a passageway adjacent the opposite side of the car, both said passageway and said main part being adapted to permit an appreciable number of persons to stand therein, and means for preventing persons in said passage and said main part from entering the body of the car until the fares are collected.

21. A passenger car having a side entrance and an enclosure within said entrance, said enclosure having a main part adjacent the entrance, and a passageway adjacent the opposite side of the car, both said passageway and said main part being adapted to permit an appreciable number of persons to stand therein, and means for preventing persons in said passage and said main part from entering the body of the car until the fares are collected, said means being operable to permit persons in the passageway to enter the main part of the car and prevent persons within the main part entering the passageway.

22. A passenger car having an entrance and a pay-as-you-enter enclosure within said entrance, said enclosure being divided into a main part and a passageway, and doors for separating said passageway from the body of the car, and the main part from the passageway to permit collection of fares in the passageway and main part separately.

23. A passenger car having an entrance and enclosure set off within said entrance, said enclosure being provided with a partition setting off a main part adjacent the entrance, and a passageway at the opposite side, said partition being foldable to an inoperative position to leave said enclosure unobstructed.

24. A passenger train and platform at which the train may receive and discharge passengers, said train and platform having means for separating entering and leaving passengers and operable upon the pay-as-you-enter principle, means on said platform and in said train being movable out of the way of entering and leaving passengers to inoperative position, the fares being collected as the persons enter upon the platform.

Signed in the presence of two subscribing witnesses.
